[57] CLAIM

The ornamental design for a door latch, substantially as shown and described.

DESCRIPTION

FIG. 1 is a perspective view of one half of a door latch showing my new design on one face of a door, which is shown in broken lines for illustrative purposes only; FIG. 2 is a perspective view of the other half of the door latch on the opposite face of said door; FIG. 3 is a plan view of the half of the door latch of FIG. 1; FIG. 4 is a side elevational view of the door latch as if viewed from the edge of the door; FIG. 5 is a right end elevational view of FIG. 4; FIG. 6 is a left end elevational view of FIG. 4; FIG. 7 is a side elevational view of the door latch opposite to that shown in FIG. 4; and FIG. 8 is a plan view of the half of the door latch of FIG. 2.
